[57] CLAIM

The ornamental design for a safety razor stand, as shown and described.

DESCRIPTION

FIG. 1 is a left, rear perspective view of a safety razor stand showing my new design in use;

FIG. 2 is a left, rear perspective view of the stand alone;

FIG. 3 is a front elevational view thereof; and

FIG. 4 is a top plan view thereof.

FIG. 1

FIG. 3

FIG. 4

FIG. 2
